UNITED STATES PATENT OFFICE.

WINTHROP WITTINGTON, OF JACKSON, MICHIGAN, ASSIGNOR TO AMERICAN FORK & HOE COMPANY, OF CLEVELAND, OHIO, A CORPORATION OF OHIO.

D TOP.

Application filed August 30, 1923, Serial No. 660,183. Renewed April 15, 1926.

This invention relates to that type of handles commonly known as D-tops suitable for various tools such as shovels, spades, forks and the like.

5 The main object of the invention is the production of a handle of this character, the body portion of which consists of sheet metal cut or stamped and pressed to desired form thereby effecting an economy in the 10 cost of production, and at the same time providing a handle that is comparatively light and yet of great strength and which readily conforms itself for assemblage with 15 wooden shanks or shafts of slightly varying size, due to the flexibility of the split tubular metal shank.

A further advantage relates to the shape 20 of the blank, and the handle formed therefrom whereby a split tubular shank is produced without undue straining or stretching of the metal.

Other objects relate to the particular form 25 of the handle whereby the desired strength and rigidity are obtained and to the means provided for preventing the wooden hand 30 grip from rotating after the handle is assembled.

In the drawings:—

Figure 1 is a plan view of the blank from 35 which the handle is formed.

Figure 2 illustrates the blank after the first operation has been performed upon it.

Figure 3 illustrates the blank after the 40 second operation has been performed upon it.

Figure 4 is a section on line 4—4, Figure 3.

Figure 5 illustrates the blank after the third operation has been performed upon it.

45 Figure 6 is a bottom plan view of Figure 5.

Figure 7 illustrates the blank after the fourth operation has been performed upon it.

50 Figure 8 is a bottom plan view of Figure 7.

Figure 9 illustrates the completed handle.

Figure 10 is a section on line 10—10, Figure 9.

55 Figure 11 is a section on line 11—11, Figure 9.

In order that the method of manufacture and the form and structure of the finished product may be thoroughly understood, the annexed drawings disclose the steps or oper-

ations carried out in the production of the complete handle by illustrating the form of the blank after each operation, and the form and structure of the completed handle.

The blank as shown in Figure 1, is very 60 much in the form of a right angle cross and comprises what may be termed an elongated strip —1— of sheet metal with integral flanges —2— and —3— respectively, extending from opposite sides of the strip at 65 substantially its central portion and disposed at substantially right angles to the axis of the strip —1—.

For the purpose of clearness of description, this elongated strip —1— may be divided 70 into three sections or parts—a central section —4— of substantially circular form, and constituting the base of the split tubular shank when the latter is formed, and two opposite extending arms —5— and 75 —6— which are subsequently bent so as to constitute with the shank base, the yoke of the handle.

The flanges —2— and —3— are adapted 80 to form the split tubular shank of the handle and preferably they are of substantially 85 equal size and of substantially identical form and each adapted to be bent into substantially semi-circular form so as to constitute one half of the split tubular shank 85 for receiving the wooden shaft.

For the purpose of facilitating the bending 90 of these flanges into the desired form and permitting their shaping into substantially semi-cylinders without undue stretching or straining of the sheet metal, the opposite longitudinal edges —7— and —8— of the flange —2— are separated from the strip —1— by slots or recesses —9— and —10— respectively, and the opposite longitudinal edges —11— and —12— of the flange —3— are separated from the strip —1— by slots or recesses —13— and —14— respectively.

All of these recesses extend substantially 100 parallel with the axis of the strip —1— and may be formed as shown in the initial production of the blank by cutting out portions of the metal at these points so as to leave the longitudinal edges of the flanges —2— and —3— free to be bent with respect to the strip —1— while the flanges are integrally connected to the part that has been termed the shank base —4—, but are separated 105 from the arms —5— and —6— al- 110

though normally they overlie portions of such arms.

The blank so shaped as illustrated in Figure 1, may be produced in any suitable way as by cutting the same from a strip of sheet metal.

The first operation performed upon this blank consists in perforating the blank or cutting out portions to form rivet openings 10 —15—, —16—, —17—, —18—, —19— and —20—.

The openings or perforations —15— and —16— are formed in the opposite extremities of the arms —5— and —6— respectively, 15 and preferably these arms taper slightly as they extend outwardly from the shank base —4— and are formed at their extremities with substantially circular shaped heads of slightly greater lateral diameter than the 20 width of the respective arm where it joins the head, and at the same operation as the rivet openings are formed, these substantially circular heads —21— and —22— are formed with corrugations which are preferably in line with the axis of the strip —1— and extend diametrically of the openings —15— and —16— and upon both sides of said openings, and are formed by pressing in narrow sections of the body of the metal 25 to form narrow projections or prongs —28— and —29— for a purpose to be hereinafter described.

The next operation consists in subjecting the blank of Figure 2 to suitable operating 30 dies or other mechanism whereby it is pressed to the shape shown in Figures 3 and 4.

That is, the flanges —2— and —3— are 40 bent downwardly at substantially right angles to the body of the strip —1— into substantial parallelism with each other while the shank base —4— is shaped in substantially circular form and the walls of the flanges —2— and —3— are slightly convexed near the shank base as illustrated at —23—.

At the same time, the arms —5— and —6— are inclined upwardly with respect to the shank base —4— and the heads —21— and —22— are extended outwardly at an angle to the respective arms in a plane approximating the horizontal.

In bending the arms —5— and —6— upwardly, they are likewise laterally convexed 55 inwardly to conform somewhat with the downward bending of the flanges —2— and —3— so as to form a symmetrical continuous structure without abrupt bends of the metal.

The next operation consists in shaping the blank of Figures 3 and 4 into the form shown in Figures 5 and 6 in which the flanges —2— and —3— are each bent into 60 substantially semi-circular form with their concavities facing each other to form a split tubular shank —24—, the slots —9— and

—10—, and —13— and —14— permitting this shaping of the tubular shank without undue stretching or straining any portions of the sheet metal.

The next operation as shown in Figures 7 70 and 8 consists in bending the concaved arms —25— and —26— with their ends in a substantially vertical position and extending from the shank base —4— along arcuate lines with the heads —21— and —22— extending upwardly from respective arms in substantial parallelism and with the corrugations or prongs —28— and —29— projecting inwardly.

In this operation, the sections of the split shank —24— may be further pressed toward each other so as to substantially close the cylinder formed thereby as best shown in Figure 8.

The handle is completed by inserting the 80 wooden hand grip —30— between the heads —21— and —22— and passing the rivet —31— through both heads and the hand grip as illustrated, and riveting or otherwise securing the same in place so as to draw the 90 heads —21— and —22— toward each other and imbed the corrugations or prongs —28— and —29— in the wooden hand grip so as to lock the latter from rotation with respect to the heads. 95

The handle may then be placed upon any suitable shaft by inserting the latter in the split tubular shank —24— and passing rivets through the aligned openings —17— and —19— and the shaft, and through the aligned openings —18— and —20— and the shaft, and securing the rivets in place.

The structure so produced is of great strength and efficiency and readily adapts 100 itself to commercial production and assemblage with the parts designed for association with it and can be produced in an economic and comparatively inexpensive manner and at a low cost.

The lines of the structure as produced, are 105 symmetrical and avoid sharp bends and undue stretching of the metal and the inward convexity of the arms —5— and —6— effects the desired strength without exposing the hands of the operator to sharp corners while adding to the ease with which the tubular tapered shank may be formed as 110 illustrated in a symmetrical manner.

Although I have shown and described an 115 exact form of blank and structure, I do not desire to limit myself to the exact form or structure of the blank or to the details of the structure of the handle, as various changes and modifications may be made 120 within the scope of the claims hereto appended.

I claim:

1. A D-top formed of a single piece of sheet metal and comprising a substantially U-shape yoke formed of a single thickness of 130

sheet metal, the intermediate portion of the yoke being substantially U-shape and convex in lateral cross-section throughout with its convexity projecting inwardly and forming at the center of the yoke a substantially flat shank base with opposite lateral edges extending downwardly from the shank base, and a pair of substantially semi-cylindrical flanges extending downwardly from the respective edges at opposite sides of the shank base and integrally connected to the respective edges throughout their central portions, and separated at opposite end portions from respective edges of the shank base by recesses of substantial width and having arcuate inner edges whereby the integral connection of the semi-cylindrical flanges to the opposite edges of the shank base may be retained throughout the greater portion of the width of said flanges and the flanges may be shaped to semi-cylindrical form without materially weakening the connection.

2. A D-top of the type referred to formed of a single piece of sheet metal and comprising a shank base and arms formed of a single thickness of sheet-metal extending outwardly and upwardly therefrom, comprising a portion channel-shaped in lateral cross-section, a hand-grip disposed between the upper ends of said arms, and a pair of substantially semi-cylindrical flanges extending downwardly from the shank base and integrally connected to the shank base throughout their central portions and separated at their opposite edges from the shank base by slots having arcuate inner edges whereby the integral connection of the cylindrical flanges to the shank base may be retained throughout the greater portion of the width of said flanges, and they may be

shaped to semi-cylindrical form without materially weakening the connection.

3. A D-top formed of a single piece of sheet metal and comprising a substantially U-shaped strip with a substantially semi-cylindrical flange extending downwardly from each side of the intermediate portion of the U-shaped strip to embrace the end of a tool handle therebetween, each of the flanges being integrally joined at its middle to a side of the said intermediate portion and separated therefrom in more laterally disposed portions by recesses of substantial width having curved inner edges, whereby the integral connection of the semi-cylindrical flanges to the opposite edges of the said intermediate portion may be retained throughout the middle portion of the width of said flanges and the flanges shaped to semi-cylindrical form without materially weakening the connection.

4. A D-top formed of a single piece of sheet metal, comprising a substantially U-shaped strip and laterally disposed downwardly depending channel shaped flanges, each integrally joined to a side of the said intermediate portion in a portion of its width but separated therefrom in another portion thereof disposed towards a side edge of the flange by a slot having curved inner edges, whereby the integral connection of the downwardly depending channel shaped flanges to the U-shaped strip may be retained throughout the non-slotted portion of the width of the flanges, while permitting the flange to be formed to channel shape, without materially weakening the connection.

In witness whereof I have hereunto set my hand this 22nd day of August 1923.

WINTHROP WITHINGTON.
